UNITED STATES PATENT OFFICE.

WALTER C. RUSS, OF NORFOLK, VIRGINIA.

DESIGN FOR A WATCH-FOB.

No. 38,429.

Specification for Design.

Patented Jan. 29, 1907.

Application filed November 30, 1906. Serial No. 345,841. Term of patent 3½ years.

To all whom it may concern:

Be it known that I, WALTER C. Russ, a citizen of the United States, residing at Norfolk, in the county of Norfolk and State of Virginia, have invented a certain new, original, and ornamental Design for a Watch-Fob, reference being had to the accompanying drawing, which shows a front view of the fob.

I claim—

The ornamental design for a watch-fob as shown.

WALTER C. RUSS.

Witnesses:

WALTER B. BURROW,
H. S. BLANKENSHIP.
